UNITED STATES PATENT OFFICE.

JOSEPH PATRICK, OF FRANKFORT-ON-THE-MAIN, GERMANY.

AUTOMATIC LUBRICATOR.

SPECIFICATION forming part of Letters Patent No. 360,243, dated March 29, 1887.

Application filed April 5, 1886. Serial No. 197,767. (No model.) Patented in Belgium May 15, 1879, No. 48,041; in England July 24, 1879, No. 3,012; in Germany August 22, 1879, No. 6,763, and in Austria-Hungary March 27, 1880, No. 946 and No. 688.

To all whom it may concern:
Be it known that I, JOSEPH PATRICK, a subject of the Queen of Great Britain, residing at Frankfort-on-the-Main, in the Empire of Germany, have invented certain new and useful Improvements in Automatic Lubricators, (and which has been patented in Belgium, May 15, 1879, No. 48,041; Great Britain, July 24, 1879, No. 3,012; Germany, August 22, 1879, No. 6,763, and Austria-Hungary March 27, 1880, Nos. 946 and 688,) of which the following is a specification.

This invention refers to a new method of feeding a lubricant to surfaces; and it consists in utilizing the fact that different metals have a different expanding coefficient when heated to the same degree; and in carrying out my invention I employ the herein-described method of automatically feeding lubricating-oil to surfaces, consisting in providing two adjacent surfaces made of different metals, which surfaces, when in a quiescent state, close the feeding of the lubricant, but when heated separate the one from the other in consequence of the different expanding coefficient of the said different metals.

In carrying this my invention into effect I construct an apparatus wherein the differential expansion of metals when heated is utilized to effect a communication between the oil-reservoir and the chamber into which the oil is to be introduced. I thus produce an automatic lubricator which has no taps, valves, wick, springs, or similar movable parts, and which will not be liable to readily get out of repair, and which cannot fail to operate.

It will at once be obvious that different metals can be used for this purpose, and that the said lubricators can be made of various sizes, shapes, and of varied construction.

The metals I have found advantageous to use are gun-metal and steel. The shape and general arrangement of the apparatus which I have found to answer in practice is represented in the accompanying drawing, wherein a lubricator is shown partly in elevation and partly in section.

The lubricator represented in the accompanying drawing consists of an outer gun-metal cup, A, in which a second gun-metal cup, B, hangs by a conical rim, K. The latter is drilled

through at b to connect the space between the cups A and B with the inside of the cup B, and thus equalizes the pressure or vacuum, as the case may be. The two cups are held tightly the 55 one within the other, and a steam-tight joint is effected by a lid, F, which is provided with an air-tight compartment, J, serving, by its non-conducting properties separating the heat inside from the cold outside, to prevent condensation in lubricators which are much exposed, as on locomotives and the like. The lid F has a hole, G, in its center, through which the apparatus is filled. A screw-cap, H, fits on the lid F, closing the hole G. A perfect 65 steam-tight joint which is not subject to premature wear with being opened and closed is effected by grinding the plug H' with emery and oil onto its seat at the top of the opening G of the lid F. The plug H', after being 70 thus adapted to its seat, is attached to the screw-cap H by the pin h in such a manner that it can adjust itself and produce a perfect joint with the top of the opening G. The bottom of the cup B has a hole bored through it, 75 into the upper conical end of which the conical point of a steel plug, C, fits, the said plug being carried by a tube, E, cast in one piece with the cup B. The plug C is screwed into the tube E, and can be adjusted as required. 80 A strainer, L, is provided, to stop any impurities which may have entered the apparatus. It will thus be seen that as soon as the said apparatus becomes warm the steel plug, expanding in a less degree than the gun-metal, 85 into which it is screwed, is lifted somewhat out of its conical seat, and a passage is thus opened, through which the oil passes partly by its own weight and partly by capillary attraction, the pressure or vacuum, as the case may be, being 90 equal above and below. When the engine or machine stops and the apparatus cools, the metals contract and the plug again tightly closes the said passage or hole, preventing all waste of oil when the engine or machine is 95 not working. The said hole cannot become stopped, as each time the metals contract the steel plug forces out any substance which may form an obstruction.

The consumption of oil can be exactly regulated by tightening or unscrewing the plug C, as the case may be. This operation can be ef-

fected with an ordinary screw-driver passed through the hole G. Freezing of the said apparatus is prevented even in the coldest weather, the space between the two cups being 5 fitted with steam, which, as soon as the machine starts, melts the oil at once.

Having thus fully described my said invention and the manner of employing the same, what I claim, and desire to secure by Letters 10 Patent of the United States of America, is—

1. In an automatic lubricator, the combination, with a cup having a discharge-passage, of a plug fitting into the said discharge-passage, the said cup and plug having different 15 expanding coefficients.

2. In a lubricating device, the cups A and B and the pin C, in combination with the lid F, having the aperture G, and the screw-cap H and plug H', substantially as shown and de- 20 scribed.

3. In a lubricating device, a lid, F, and an air-chamber attached to the said lid, in combination with the cups A and B, substantially as shown and described.

25 4. In a lubricating device, the cups A and

B, in combination with the lid F, the inner cup, B, provided with the two-sided conical rim K, which holds the said cups concentrically to each other, substantially as shown and de- 30 scribed.

5. In a lubricating device, the cup A and the lid F, in combination with the cup B, pro- 35 vided with the conical rim K, forming a steam-tight joint without packing, substantially as shown and described.

6. In a lubricating device, the cup A, the cup B, suspended in the cup A, the lid F, hav- 40 ing the air-chamber J, and the screw-cap H, in combination with the steel plug C, fitted to screw in the projection E, formed in the bot- 45 tom of the cup B, substantially as shown and described.

In testimony whereof I have signed my name to this specification in the presence of two sub- 50 scribing witnesses.

JOSEPH PATRICK.
